US0D1002605S

(12) **United States Design Patent** (10) **Patent No.:** **US D1,002,605 S**
(45) **Date of Patent:** **** Oct. 24, 2023**

(54) **ELECTRONIC DEVICE**

- (71) Applicant: **Apple Inc.**, Cupertino, CA (US)
- (72) Inventors: **Bartley K. Andre**, Palo Alto, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steven P. Jobs**, Palo Alto, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Douglas B. Satzger**, Menlo Park, CA (US); **Calvin Q Seid**, Palo Alto, CA (US); **Christopher J. Stringer**, Woodside, CA (US); **Eugene Antony Whang**, San Francisco, CA (US); **Rico Zörkendörfer**, San Francisco, CA (US)
- (73) Assignee: **Apple Inc.**, Cupertino, CA (US)
- (**) Term: **15 Years**
- (21) Appl. No.: **29/845,816**
- (22) Filed: **Jul. 11, 2022**

Related U.S. Application Data

- (60) Continuation of application No. 29/661,379, filed on Aug. 27, 2018, now Pat. No. Des. 957,385, which is a continuation of application No. 29/563,704, filed on May 6, 2016, now Pat. No. Des. 826,929, which is a continuation of application No. 29/471,703, filed on Nov. 4, 2013, now Pat. No. Des. 755,784, which is a continuation of application No. 29/432,435, filed on Sep. 14, 2012, now Pat. No. Des. 692,879, which is a continuation of application No. 29/394,296, filed on Jun. 15, 2011, now Pat. No. Des. 673,949, which is a continuation of application No. 29/384,735, filed on Feb. 3, 2011, now Pat. No. Des. 673,947, which is a

continuation of application No. 29/366,850, filed on Jul. 30, 2010, now Pat. No. Des. 633,091, said application No. 29/394,296 is a continuation of application No. 29/345,051, filed on Oct. 8, 2009, now abandoned, said application No. 29/366,850 is a continuation of application No. 29/344,620, filed on Oct. 1, 2009, now Pat. No. Des. 622,270, said application No. 29/345,051 is a division of application No. 29/284,272, filed on Sep. 5, 2007, now Pat. No. Des. 604,297, said application No. 29/344,620 is a continuation of application No. 29/284,188, filed on Aug. 31, 2007, now Pat. No. Des. 602,486.

CLAIM

The ornamental design for an electronic device, as shown and described.

DESCRIPTION

FIG. 1 is a front perspective view of an electronic device showing the claimed design;

FIG. 2 is a rear perspective thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures show portions of the electronic device that form no part of the claimed design.

FIGS. 1-8 are illustrated to show contrasting appearance.

Areas of the electronic device that appear in different shades of gray/black represent areas with contrasting appearance.
